UNITED STATES PATENT OFFICE.

JOHN A. SWANSON AND AUGUST W. LINTON, OF FARGO, DAKOTA TERRITORY.

MACHINE FOR MAKING BRICK FROM DRY MATERIAL.

SPECIFICATION forming part of Letters Patent No. 348,702, dated September 7, 1886.

Application filed March 4, 1886. Serial No. 193,948. (No model.)

To all whom it may concern:

Be it known that we, JOHN A. SWANSON and AUGUST W. LINTON, citizens of the United States, residing at Fargo, in the county of Cass, Dakota Territory, have invented certain new and useful Improvements in Machines for Making Brick from Dry Material; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our brick-press is designed for pressing brick from dry pulverized material, so that as fast as the bricks are pressed and dropped out of the molds they may at once be burned.

In the accompanying drawings, Figure 1 is a side elevation of our brick-press, part of it being in section and a part of it, deemed unnecessary to be shown, broken away. Figs. 2, 3, and 4 are detail views of the same.

Our invention is described as follows:

Referring to the drawings, Fig. 1, A A' A² A³ represent the parts of the frame wherein the machinery proper is mounted. A² and A³ are made in pairs; but to more plainly show the working of the machine the front pair is removed. The power for operating the machine is applied by means of a belt working on a pulley-wheel, B, and through said pulley and a double set of gearing, B', it is communicated to a crank, C, pitman D, balance E, and thrust-bar F, to the reciprocator G. Reciprocator G is pivoted on a strong journal or pin, H, and the lower reciprocator, I, is pivoted on another strong journal, H'. Thus by a continuous motion of the gearing B' the reciprocator G obtains a rocking motion, which it imparts to the lower reciprocator, I, through the sliding block J. It will be seen that the dies K and L, which move perpendicularly in the guides M and N, and connected to reciprocators G and I by means of sliding blocks O and P, will at one oscillation of the reciprocators, move toward each other, and at the return oscillation move away from each other.

Q is the molding-table, containing eight brick-molds, R. This molding-table is mounted on a shaft, S, journaled in a bearing, S' and

step S². There is also keyed on shaft S, a four-toothed ratchet-wheel, S³, for the purpose of turning the molding-table Q ninety degrees to every reciprocation of the dies. This turning of the table is accomplished by means of a ratchet-bar, S⁴, and a knee-lever, S⁵, actuated by lever E by means of a bar, S⁶, pivoted to the short end E' of the said lever E and to the lower end of the knee-lever S⁵, said ratchet-bar being hollowed out to work over the said ratchet-wheel S³.

T is part of a stationary segment, which, at the place where the dies enter, is provided with holes T', corresponding with the brick-molds R.

Now, as the pulverized material is conveyed by the conveyer U it drops into the two molds R at that place and on top of the segment T, and is carried by the mold-board Q ninety degrees to the right, where the two dies K and L will by that time be ready to press the pulverized material to the proper size of a brick. After the bricks are pressed they follow the table or mold-board to a point diametrically opposite to where they are pressed, and are then pushed out of the molds by means of the walking-beam V, pitman V', and plunger V², and conveyed to the desired place by another conveyer, U', the short end of said walking-beam V being connected with and operated by reciprocator G, pitman G', and its long end with the pitman V', and said pitmen with said plunger V². In order to effect a quick return-stroke of the dies K and L, the following mechanism (shown in Fig. 1) is used. When the return-stroke begins, the spring-hook W' catches on the angle-lever W², thereby pushing the rod W³ through the slide-block W⁴, and thrusts the bar F off from the end E' of the lever E, and by so doing the reciprocators and everything connected with them is left to the action of a strong spring, X, which quickly effects the return-stroke.

As the lever E is nearing its highest point, the spiral spring W on rod W³ brings thrust-bar F in the proper position on the upper edge of the end E' of the lever E. The spring X has its large end bolted to the frame A', while its small end is pivoted to the lower end of a rod, X², whose upper end is pivoted to the arm X³ of the reciprocator I. If we wish to stop the press and mold-table, we pull hand-

lever Y over a knob, Y', on the segment Y², thereby disengaging thrust-bar F, by means of the rod Y⁶, from contact with the main press-lever E, thus stopping the motion of the press.

5 At the same time hand-lever Y pulls bar Y³, containing block Y⁴, against the tail part of the ratchet-dog Y⁵, disengaging it from contact with ratchet-wheel S³, thus stopping the motion of the molding-table Q. The wheel-work and main press-lever E may thus be running while the press proper and mold-board are at rest.

In Fig. 4 is shown an inverted view of the mold-table, showing the segment T covering two of the holes or molds R. These two molds covered are the ones being filled by the conveyer U. This segment T is stationary, while the mold-table Q moves over it.

This machine is made adjustable wherever necessary.

Having described our invention, what we claim as new, and desire to secure by Letters Patent, is—

1. The combination, with the frame A A' A² 25 A³, pulley B, double gearing B', and crank C, of pitman D, its upper end pivoted on the arm of crank C, its lower end pivoted to the long arm of the balance E, balance E, fulcrumed on the lower part of said frame, thrust-bar F, its lower end working on the short arm E' of the balance E, its upper end pivoted to the outer arm of the reciprocator G, reciprocators G and I, pivoted to the said frame by journals H and H', and pivoted together by 35 sliding block J, dies K and L, pivoted to the inner arms of the said reciprocators by means of sliding blocks O and P, and working up and down in the guides M and N, substantially as shown and described.

4c 2. In a brick-machine, as above described, the combination, with the balance E, of the bar S⁶, one end pivoted to the short end E' of the said balance, and the other end pivoted to the lower end of knee-lever S⁵, knee-lever S⁵, 45 pivoted to the frame of said machine, ratchet-bar S⁴, one end having a mortise in which the upper end of said knee-lever works, dog Y⁵, pivoted in said bar and working in the ratchets of ratchet-wheel S³, ratchet-wheel S³, keyed on 50 shaft S, shaft S, journaled in the bearing S' and step S², and molding-table Q, rigidly mounted on the upper end of said shaft, said table revolving on the upper face of a stationary segment, T, substantially as shown and 55 described, and for the purposes set forth.

3. In a brick-machine, as above described, the combination of the double gearing B', having the crank C, pitman D, its upper end pivoted to the arm of said crank and its lower 60 end to the long arm of balance E, balance E,

fulcrumed on the lower part of the frame of said machine, spring-hook W', pivoted to the lower part of said frame, angle-lever W², pivoted to the side of balance E, one end adapted to catch in the spring-hook W', its other end 65 having pivoted therein rod W³, spiral spring W, sliding block W⁴, pivoted in a seat bolted to the upper edge of balance E, rod W³, working through said spiral spring W, and sliding block W⁴, one end pivoted to angle lever W² 70 and the other grasping in its mortise the lower end of thrust-bar F, substantially as shown and described, and for the purposes set forth.

4. In a brick-machine, as above described, the combination of the lever Y, rod Y⁶, one 75 end attached to said lever and the other to the rod W³, rod W³, grasping in its mortise the lower end of thrust-bar F, bar Y³, block Y⁴, attached to bar Y³ and adapted to strike against the tail part of the dog Y⁵, thereby disengaging it from contact with the ratchet-wheel S³, said lever Y having its lower end pivoted to the frame of said machine and its middle part adapted to catch over the knob Y' on segment Y², substantially as shown and 85 described, and for the purposes set forth.

5. In a brick-machine, as above described, the combination of the spring X, its butt-end bolted to the frame of said machine, rod X², its lower end pivoted to the spring end of said 90 spring and its upper end to the arm X³ of the reciprocator I, reciprocator I, journaled to said frame and pivoted to the reciprocator G by means of sliding block J, reciprocator G, journaled to said frame, pitman-rod G', pivoted to said reciprocator G and walking-beam V, walking-beam V, fulcrumed on said frame, pitman V', pivoted to said walking-beam and 95 to the plunger V², plunger V², working up and down in its guides, substantially as shown and 100 described.

6. The combination of the frame A A' A² A³, pulley B, double gearing B', crank C, pitman D, balance E, thrust-bar F, reciprocator G, having die K attached to its inner arm, reciprocator I, having die L attached to its inner arm, pitman G', walking-beam V, pitman V', and plunger V², working up and down in the guides, bar S⁶, attached to the balance E, knee-lever S⁵, bar S⁴, dog Y⁵, ratchet-wheel S³, 105 shaft S, molding-table Q, segment T, and carriers U and U', substantially as shown and described, and for the purposes set forth.

In testimony whereof we affix our signatures in the presence of two witnesses.

JOHN A. SWANSON.
AUGUST W. LINTON.
